UNITED STATES PATENT OFFICE.

LORENZ IVERSEN, OF PITTSBURG, PENNSYLVANIA.

EXPLOSIVE-ENGINE.

No. 858,071.

Specification of Letters Patent.

Patented June 25, 1907.

Application filed December 18, 1905. Serial No. 292,241.

To all whom it may concern:

Be it known that I, LORENZ IVERSEN, of Pittsburgh, Allegheny county, Pennsylvania, have invented certain new and useful Improvements in Explosive-Engines, of which the following is a specification, reference being had to the accompanying drawings, wherein—

Figure 1 is a vertical sectional view of a two-cylinder engine constructed in accordance with the invention, the movable parts being shown in their normal positions of rest. Fig. 2 is a vertical cross-sectional view on line 2—2 of Fig. 3. Fig. 3 is a view similar to Fig. 1, showing the oppositely acting pistons at the limits of their stroke. Fig. 4 is a cross-sectional view, taken on line 4—4 of Fig. 3. Figs. 5 and 6 are detail views.

This invention relates primarily to two-cycle multiple cylinder explosive engines, and one object is to provide improved means for admitting the explosive charges; also novel means for having each entering charge preceded by a scavenger charge of air.

A further object is to utilize the crank-case of the engine as a compressed air-reservoir, and to utilize this compressed air in forming the explosive charges, also for expelling the exploded gases from the cylinders in advance of each entering fresh charge.

Still a further object is to so connect the piston of an auxiliary cylinder to the engine that it may be utilized for starting the latter, the movement of the piston being preferably controlled by reversible valves whereby the engine may be started in either direction.

In the preferred embodiment of the invention, the auxiliary cylinder and piston are utilized as a compressor for supplying the crank-case with air, provision being made in such embodiment for having the pump either draw from the atmosphere as when operating as a compressor, or supplied with air under pressure, as when starting the engine.

With these and other objects in view, as will presently appear, the invention consists in the novel features of construction, and in the combination and arrangement of parts hereinafter fully described and claimed.

Referring to the drawings, 2 designates the crank-case, and 3 the crank-shaft. Seated side by side in the top of the crank-case and projecting thereinto are the elongated cylinders 4 and 5. These cylinders,

respectively, in conjunction with the crank-case, form cylinder-encircling chambers 6 and 7, with the cylinders provided, respectively, with lateral ports 4' and 5' opening into said chambers. The ends 8 of the cylinders are of neck-like form and open into exhaust-chamber 9.

The pistons 10 and 11 are so connected to the cranks of shaft 3 as to work opposite to each other or in reverse order. The pistons have stem-like extensions 10' and 11', respectively, which move in cylinder-necks 8, the outer ends 12 and 13 thereof being of tubular form and open at their outer extremities and having lateral ports 12' and 13', respectively, each of which in one extreme position of the piston is open to its cylinder and in the other position to exhaust-chamber 9. On the exterior of the cylinders, chambers 6 and 7 are connected by the passage-way 14 which intersects mixing chamber 15.

The lower ends of the cylinders are open to the crank-case as shown, and with air maintained in the latter under pressure, in manner presently to be described, the operation is as follows: Referring to Fig. 3, piston 10 has just completed its upward or compression-stroke, and in so doing has moved above and uncovered ports 4', admitting therethrough air under pressure from the crank-case to chamber 6 and through passage 14 to mixing chamber 15 where the fresh charge is formed for cylinder 5. Simultaneously, piston 11 has completed its explosion or power-stroke and in so doing has uncovered ports 5', with exhaust-ports 13' within the cylinder. The forward pressure in passage 14 and through the mixing-chamber forces ahead of it the air in chamber 7, and hence this air is the first to enter cylinder 5 through ports 5' and serves as a scavenger charge or stratum interposed between the exploded gases and the entering fresh charge, preventing the same from intermingling and avoiding danger of a premature explosion which direct contact would cause.

This arrangement also prevents any appreciable part of the fresh charge from being wasted, the operation being so timed that piston 11 starts on its upward or compression-stroke and closes ports 13' concurrently with the passage of the last of the exploded gases, or at the instant the interposed stratum of air is passing therethrough. As ports 4' close simultane-

ously with ports 5', chamber 6 is left filled with a volume of air which in the charging of cylinder 4 (when the positions of the pistons are the reverse of that indicated in Fig. 3) 5 enters the latter in advance of the fresh charge, and forms the interposed scavenger charge or air stratum above described, the propelling pressure at such time emanating from ports 5' and chamber 7. Thus, when 10 charging each cylinder a volume of fresh air is ahead of the explosive charge and only awaits the uncovering of the ports at the completion of the explosion or power-stroke to enter the cylinder and force out the exploded gases. 15 For maintaining air under pressure in crank-case 2, a cylinder 16 is mounted thereon in manner similar to cylinders 4 and 5, and is formed with piston or pump-chamber 17, having its piston 18 connected to a crank of 20 shaft 3. At one side of cylinder 16 is valve-case 19 having opposite ends thereof in communication with the crank-case, as indicated at 20, Fig. 2. At opposite ends of chamber 17 are ports 21 and 21' through which valve-case 19 is adapted to communicate with said chamber. Within casing 19 is a tube-like bushing, slotted between its ends as indicated at 22, and having grate-like ends 23. 25 On the outer face of each of these grated ends is an outwardly opening flap-valve 24. Opposite ends of said bushing are of cylindrical form and provided with ports 25 in the planes of ports 21 and 21', and adapted to cover and close these ports are the upper and lower 30 valve-heads 26 and 26', said heads being secured to stem 27. A valve-gear and link-motion 28 connects stem 27 with crank-shaft 3, whereby the valves are operated, and may be so manipulated when starting the engine 35 as to cause piston 18 to move either downward or upward as desired. Air for the pump enters casing 19 through side-slots 22 and passes to cylinder-port 21 or 21', according to the positions of the valves. Thus, 40 with valve 26 above port 21 and valve 26' above port 21', piston 18 will at such time be moving downward and drawing air through port 21 and at the same time forcing the air beneath the piston out of port 21' and 45 through the lower grated end 23 of the bushing and into the crank-case. At the completion of the stroke of piston 18, the positions of valves 26 and 26' are reversed by the valve-gear and the operation is repeated with 50 the valves in that position.

The air ingress 29 for valve-case 19 is provided with an inlet 30 from the atmosphere, controlled by the normally open valve 31. As the engine may be conveniently started 55 by the admission of air under pressure to pump-cylinder 17, a compressed air-connection 32 is provided, normally closed by spring-valve 33. For operating these valves simultaneously, a rock-shaft 34 may be projected 60 therebetween and carry a lug 35 for lifting

and closing valve 31 and a similar lug 36 for depressing valve 33, shaft 34 being provided with an arm 37 or other suitable device for operating it. The pressure within cylinders 4 and 5 and crank-case 2 are such that when 70 the engine is stopped, the pistons come to rest in approximately the half-way position indicated in Fig. 1. When starting the engine, if it is desired to have it operate in the direction in which it last operated, it is only necessary to so manipulate shaft 34 as to close valve 31 and open valve 33, thus admitting air under pressure to pump-cylinder 17 which starts piston 18 and as the latter is connected to and operates with the crank-shaft, the engine-pistons are started simultaneously. As 75 soon as the start has been made, valve 33 is closed and valve 31 opened, when cylinder 17 and piston 18 resume their normal pumping or compressing function. If the engine 80 is to be started in a reverse direction to that in which it last operated, it is only necessary to reverse the positions of valves 26 and 26' by shifting link mechanism 28, a rod 28' being provided for that purpose. 85

The engine-cylinders, pump-cylinders, and valve-case are inclosed by jacket 38 which provides space for circulation of water around all of the working parts, maintaining them at proper temperature. The ignition mechanism, which may be of any approved construction, is not shown as it forms no part of the invention. 90

While the auxiliary cylinder and pump are preferably utilized as a compressor, the 100 invention is not limited thereto, and whether so used or not, it will be understood that air under pressure may be derived from any suitable source for starting the engine. And while the crank-case is preferably utilized as 105 the air-reservoir, the latter may be variously embodied and located.

The arrangement and adaptation shown whereby the pump may be utilized both as a compressor and for starting the engine in 110 either direction, is particularly desirable, as thereby an explosive engine is provided which may be quite as conveniently reversed as a steam engine, and the usual annoying and laborious cranking operation is eliminated. 115

I claim:—

1. In an explosive engine, the combination with an engine cylinder, and a piston and crank-shaft, of a compressed air reservoir 120 communicating with the cylinder, a pump for the reservoir having its piston connected to the crank-shaft, and means for admitting air from the atmosphere and air under pressure to the pump. 125

2. In an explosive engine, the combination with an engine cylinder, and a piston and crank-shaft, of a compressed air reservoir communicating with the cylinder, a pump for the reservoir having its piston connected 130

to the crank-shaft, reversible valve mechanism for the pump operatively connected to the crank-shaft, and means controlled by the valve mechanism for admitting air from the atmosphere and air under pressure to the pump cylinder.

3. In an explosive engine, the combination with an engine cylinder, and a piston and crank-shaft, of a compressed air reservoir communicating with the cylinder, a pump for the reservoir having its piston connected to the crank-shaft, a valve case in communication at its ends with the pump cylinder and with the reservoir, connected valves in valve case for controlling communication with the cylinder, reversing gear connecting the valves and crank-shaft, and means for admitting air from the atmosphere and air under pressure to the valve case.

4. In an explosive engine, the combination with a crank-case adapted to form a compressed air-reservoir for the engine, and a crank-shaft, of an air-pump for the crank-case having its piston connected to the shaft, reversing valves for the pump, and valve-actuating means extending from the crank-shaft.

5. In an explosive engine, the combination with a crank-case adapted to form a compressed air-reservoir for the engine, and a crank-shaft, of an air-pump for the crank-case having its piston connected to the crank-shaft, a valve-case communicating at its ends with the crank-case and pump-cylinder and between its ends having an air-supply, valves in the valve-case for controlling communication between the same and the pump-cylinder, and valve-operating means.

6. In an explosive engine, the combination with a crank-case adapted to form a compressed air-reservoir for the engine, and a crank-shaft, of an air-pump having its piston connected to the crank-shaft, a valve-case having its opposite ends in communication with the crank-case and with the pump-

cylinder, connected valves in the valve-case for controlling communicating between the same and the pump-cylinder, an operative connection between the valves and the crank-shaft, and valve-reversing means.

7. In an explosive engine, a crank-case adapted to form a compressed air-reservoir, a crank-shaft, engine cylinders communicating with the crank-case, oppositely working pistons in the cylinders, the cylinders having lateral ports at one end communicating with each other independently of the crank-case and adapted alternately to be placed in communication with the latter by the movements of the pistons, the ports of one cylinder being open to that cylinder simultaneously with the ports of the other cylinder being open to the crank-case, an air-pump for the crank-case having its piston connected to the crank-shaft, a valve-case having its opposite ends communicating with the crank-case and pump - cylinder, reversible valves for the valve-case, and means for placing the valve-case in communication either with the atmosphere or with a source of air under pressure.

8. The combination of a cylinder, a piston, a valve-case, ports at opposite ends of the cylinder open to the valve-case, a compressed air-reservoir with which opposite ends of the valve-case communicate, separated check-valves in the valve-case each adapted to open toward said reservoir, connected valves operative in the valve-case between the check-valves for placing the cylinder-ends alternately in communication with the air-reservoir and with the valve-case between said port-controlling valves, and an air-inlet for the valve-case between said last mentioned valves.
